AUGUST SUNDH, OF YONKERS, NEW YORK, ASSIGNOR TO OTIS ELEVATOR COMPANY,
OF JERSEY CITY, NEW JERSEY, A CORPORATION OF NEW JERSEY.

MAGNETIC TRACTION-WHEEL DRIVE.

974,447.

Specification of Letters Patent. Patented Nov. 1, 1910.

Application filed December 16, 1905, Serial No. 291,986.

To all whom it may concern:

Be it known that I, AUGUST SUNDH, a citizen of the United States, residing in the city of Yonkers, in the county of Westchester and State of New York, have invented a new and useful Improvement in Magnetic Traction-Wheel Drives, of which the following is a specification.

My invention relates to traction elevator systems, and one of its objects is the provision of simple and efficient magnetic traction driving apparatus.

Another object of my invention is to provide a magnetic traction wheel drive combined with means for automatically magnetizing substantially only that portion of the wheel that is in engagement with the hoisting cable or cables.

Other objects of the present invention will appear hereinafter, the novel combinations of elements being pointed out in the claims.

In the accompanying drawings, Figure 1 represents more or less diagrammatically an electric elevator system illustrating the application of my invention; Fig. 2 illustrates a side view, partly in section, of the magnetic traction driving sheave; and Fig. 3 is a plan view thereof, also partly in section; Fig. 4 represents diagrammatically the windings and connections for effecting the magnetization of a predetermined portion of said sheave; and Fig. 5 is a detail view of the brake mechanism carried by the car.

Referring particularly to Fig. 1, it will be observed that the elevator car C is provided with the usual guide shoes 1, 1 at the upper portion thereof and is adapted to be moved up and down in an elevator well by means of the driving apparatus comprising the motor M and the magnetic traction sheave T. G, G designate the guide rails, D the brake mechanism secured to the bottom of the car, S an electric switch in the car and 2 the hoisting ropes which pass over the sheaves 3, 3' mounted on the overhead beam 4, and thence downwardly to the traction sheave T and upwardly to the counterweight sheave 5 and counterweight W.

The sheave 5 is shown mounted on an additional overhead beam 4' which may be in the same horizontal plane with the beam 4, or the sheaves 3' and 5 may be on opposite sides of the beam 4. The counterweight is adapted to move over suitable stationary guides and is provided with brake mecha-

nism which is shown in this instance as similar to that mounted on the bottom of the car.

The motor M is mounted on a bed-plate 6 which is shown as supporting also the brake B adapted to be applied to the brake pulley P. The traction sheave or wheel T is fixed to the motor shaft 7 so that when the motor is operated the car will be hoisted or lowered depending upon the previous operation of the controlling apparatus.

In Fig. 5, I have shown in detail a brake for the car and counterweight, although any other suitable brake could be used, that here shown being merely for the sake of illustration. Clamps 9, 9 are arranged to be actuated by the springs 10, 10 to grip the guides and stop the car. These springs encircle extensions 12, 12 of the magnet cores 12', 12' between the collars 11, 11 fixed to said extensions and the magnet casing 14. The rods 12, 12 are connected to the clamps and are adapted to move in suitable bearings 13, 13. Normally the clamps grip the guides, but when the magnet solenoid 15 is excited with electric current the clamps are released and the car may be moved.

The motor-controlling apparatus comprises reversing switches R, R', preferably mounted on the controller board near the motor, a manual switch S in the car, accelerating apparatus A, and the brake B. When the lever 99 is moved onto the contact 16 and the main line switch L is closed a circuit will be closed through the solenoid 20' to operate the reversing switch R'. This circuit may be traced from the positive main through wires 18 and 19 to and through solenoid 20', wire 21, contact 16, lever 99, wires 22, 23 and 24 to the negative main. The switch R' will thereupon be closed and the motor circuit will then be completed from the positive main through wire 18 to and through contacts 25, 26, wires 27, 28 and 29, armature brush 30, armature 32, brush 31, wire 33, starting resistance 8, wire 34, contacts 35, 36, wires 37, 23 and 24 to the negative main. The shunt field circuit will be closed by the auxiliary switch X', the circuit being from the positive main by way of wire 18, contact 38, bridge piece 39, contact 40, wire 41, motor terminal 42, shunt field circuit (not shown), motor terminal 43, wires 44 and 24 to the negative main.

It should be noted that when the armature

circuit is closed by the reversing switch R', a circuit is closed in shunt to the armature from the point 45 by wire 46, through the magnet solenoid 15 of the brake apparatus attached to the car, and thence by wire 47 through the magnet solenoid 15' of the counterweight brake mechanism; from here the circuit continues by way of wire 48 through the motor brake magnet 49 and wires 50 to the terminal 51 of the traction wheel circuit connections. This terminal is connected to a commutating apparatus as shown in Fig. 4, so that the circuit may be further traced through the windings 52 to terminal 53, and then through wires 54 to point 55. The solenoids 15, 15', 49 and 63 are herein shown in series with each other in a circuit across the armature. This circuit could be connected directly across the mains and said solenoids could also be connected in parallel with each other if desired. The reversing switch R' being thus operated by moving the lever 99 of the car switch to its right-hand position, the car brake, counterweight brake and motor brake will be released and the motor may start at a slow speed since the current fed to the same is limited by the starting resistance 8.

Any well-known means for gradually short-circuiting this resistance may be used for accelerating the motor to full speed. I have in this instance shown by way of illustration a plurality of electromagnets arranged in series in a circuit in effect connected across the armature between the points 45 and 55. Adjustable stop screws 56 in a fixed piece 57 limit the downward movement of the magnet cores which carry at their upper ends contact-makers 58 for bridging the contacts 59 connected to the resistance 8 at various points. It will be seen that these bridging pieces are at different distances from the fixed contacts 59 so that as the counter-electro-motive force of the armature gradually builds up the current through the accelerating magnets gradually increases in strength and the magnets therefore fly up one after another to successively close their switches and step-by-step short-circuit the resistance 8.

By reference to Figs. 2 and 3 it will be seen that the wheel T is in reality a multipolar electromagnet, its poles 64 being radial and each provided with a winding or coil of insulated wire. Said wheel or sheave comprises a hub 60, web 61 and rim 62. The hub is suitably secured to the motor-shaft 7. The web may be replaced by spokes and the construction of the sheave otherwise varied as desired so long as it is of requisite strength and composed of material that is easily magnetized and de-magnetized by electric current passing through solenoids which encircle the poles. The wheel may be cast solid and slots 65 cut in afterward

to form any desired number of poles or said slots may be formed by the mold itself in casting. Furthermore, if desired, the poles may be made removable in which case they could be easily replaced if injured or the hub-and-web portion could be constructed of different material. The slots are herein shown at substantially right angles to the plane of the sheave T but I do not desire to be restricted to this exact construction as 75 the slots may be arranged diagonally. Grooves 67 are also formed in the periphery of the wheel in any desired manner and rims 66, 66' provided to prevent the hoisting ropes from being easily thrown off. In 80 order to make a solid wheel of increased strength the slots may be filled with non-magnetic material.

One or more hoisting ropes may be used. I have herein shown four, but since they move 85 together they may be considered as separate strands of a single rope if desired. Of course it is necessary in order to accomplish some of the objects of this invention that the hoisting rope be of some magnetic material and it is preferable that this material be such as will lose its magnetism very easily though this particular feature is not essential.

It may be explained that the principle of my invention is based on the fact that if the frictional contact between the hoisting ropes and the driving pulley, sheave or wheel T is increased the tendency of said wheel to slip on the ropes is very much diminished. Furthermore, more power can be efficiently exerted in operating a car heavily loaded as the traction drive may be increased without causing any slipping. For instance, if the load in the car is very heavy and the brakes 105 are all released the car might be moved downwardly by reason of excessive underbalanced load. The hoisting ropes would therefore slip but to allow such a load to be safely moved up or down, I increase the 110 traction effect of the wheel T by transforming the same into a multipolar electro-magnet. If desired the driving sheave may be composed of one or more permanent magnets instead of electro-magnets. 115

It is evident that the weight of the car and load acting on one end of the hoisting ropes and the weight of the counterweight acting on the other end thereof will effect a frictional engagement of the ropes with substantially half of the periphery of the driving sheave T, but this alone and without any intermediate friction producing sheaves would ordinarily not be sufficient. To eliminate such intermediaries and thus decrease the wear on the ropes due to bending, I magnetize the sheave preferably with electric current acting on electro-magnets, which in turn attract the ropes into firmer frictional engagement with the driving sheave. 130

It should be noted that if all the poles of this magnet were energized the hoisting rope would tend to be drawn out of vertical alinement as shown at 2' in Fig. 2 in dotted lines, thus putting a wearing strain on the rope and also unnecessarily retarding the movement thereof. To overcome this difficulty I provide a commutating arrangement so that each electro-magnet is deenergized when the rope is about to move out of engagement with its pole, as shown, for example, in the lower part of Fig. 2; and again energized when it returns into engagement substantially throughout its whole length with said rope as shown at the upper side of Fig. 2. In this instance I have shown a small support 69 (Fig. 1) secured to one of the motor shaft bearings 71 mounted on the standard 70. Secured to the upper end of the support 69 is an insulated spring pressed brush 72 in sliding engagement with the slip ring 73 secured to but insulated from the web 61 of the wheel T.

Intermediate the brush 72 and the bearing 71 is connected a bar or rod constituting the terminal 51. On the inner end of this rod is fastened or pivoted the brush holder 74 carrying a plurality of brushes 75 electrically connected to each other and bearing on the segments 76 of the commutator connected to the hub 60 of the wheel T. If desired, the brush holder support 69 may be rotatably mounted so that the brushes could be shifted to various positions depending upon the position of the traction wheel T with respect to the overhead sheaves 3' and 5, that is, whether directly under the latter or to one side or even above if the hoisting apparatus is placed at the top of the elevator well. Furthermore, the length of the brush holder may be increased or decreased so as to engage a greater or less number of segments in order to effect the energization of a predetermined number of coils 78 at one time. The brushes 75 may be separately mounted in the brush holder 74 at equal distances or irregularly but since they are electrically connected together these brushes could be replaced by a single arc shaped brush of the requisite length, if desired. The separate brushes are preferable, however, as they permit better adjustment and can be easily replaced when worn out.

When the parts are in the position shown in Fig. 4 the current may enter at the + terminal 51' and pass by way of brush holder 74 and brushes 75 to several of the segments of the commutator and thence through the magnet coils which are preferably so arranged that the poles are alternately of north and south polarity. By the addition of another brush, coil 88 could also be excited or the brush holder could be shifted so that coil 88 would be energized and coil 87 deenergized. The coils on the lower side of

the wheel are thus connected in parallel with each other, 79 designating the common return connection to the — main. It is evident that as the wheel revolves and the commutator segments pass under and away from the brushes only a predetermined number of coils are maintained energized and the parts may be so constructed and arranged that each magnet will be energized when its face is in engagement throughout its length with the ropes 2 and each upwardly moving magnet will be deenergized as the rope is about to leave said face, but obviously any other adjustment may be made. It may in some instances be found desirable to energize a particular pole while the rope is in contact with a portion of its face. This is shown in Fig. 4 where, assuming that the car is being lifted and consequently the wheel T rotating in a clockwise direction, the coil 89 is about to be energized, the coil 78 about to be deenergized, and coil 88 is already deenergized. By adding another brush coil 88 could be kept energized for a little longer time so that diametrically opposite coils, as 90 and 90 87, could be deenergized and energized respectively at substantially the same time. In the position shown in Fig. 2 coil 90 should have already been deenergized and coil 86, or both coils 86 and 87, energized. 95

Without limiting myself to the precise construction of details or arrangement of parts herein shown and described, what I claim and desire to have protected by Letters Patent of the United States is:

1. In a traction elevator, the combination with a car, and counterweight, of brake apparatus for said car and counterweight, hoisting cables connecting said car and counterweight, a magnetic sheave associated with said cables, a motor for driving said sheave, and means for simultaneously energizing said sheave and releasing said brake apparatus.

2. In a traction elevator, the combination with a car, of electro-mechanical brake apparatus carried thereby, a counterweight, additional electro-mechanical brake apparatus carried by said counterweight, one or more cables connecting the car and counterweight, a magnetic sheave associated with said cables, a motor for driving said sheave, and means for energizing said sheave and releasing said brake apparatus concurrently.

3. In a traction elevator, the combination with a car, of a counterweight, brake apparatus carried by one of said parts, a magnet for releasing said brake apparatus, one or more cables connecting the car and counterweight, a magnetic traction sheave, windings for said sheave, a motor for driving said sheave, and means operable from the car for simultaneously energizing said brake magnet, sheave windings, and motor.

4. In a traction elevator, the combination

- with a car, counterweight and cables, of 40
brake apparatus for the car and counter-
weight, electric releasing means for said
brake apparatus, an electro-magnetic traction
sheave associated with said cables, means
controllable from the car for operating said
electric-releasing-means and effecting the
energization of said traction sheave, and a
motor for driving said sheave.
5. In a traction elevator, the combination
with a car, counterweight and cables, of 45
brake apparatus for the car, electric releasing
means for said brake apparatus, an electro-
magnetic traction sheave, a motor for driv-
ing said sheave, reversing switches for the
motor controllable from the car, and connec-
tions between said reversing switches and
said electric releasing means and electro-
magnetic traction sheave to effect the opera-
tion of the releasing means and the energiza-
tion of said traction sheave when either re-
versing switch is closed.
6. In a traction elevator, the combination
with a car, counterweight and cables, of 50
brake apparatus for the counterweight, elec-
tric releasing means for said brake appa-
ratus, an electro-magnetic traction sheave
associated with said cables, means control-
lable from the car for operating said elec-
tric-releasing-means and effecting the ener-
gization of said traction sheave, and a motor
for driving said sheave.
7. In a traction elevator, the combination
with a car, counterweight and cable, of a 55
traction sheave, a motor, means for supply-
ing power to the motor, and electromagnetic
means for automatically increasing the trac-
tion between the cable and sheave when
power is supplied to the motor, and decreas-
- ing said traction when power is cut off from the motor.
8. In a traction elevator, the combination
with a car and counterweight, of brake 60
mechanism for one of said parts, a driving
rope or cable, a traction sheave, means for driv-
ing the sheave, an electromagnetic device
for increasing the traction between the
sheave and rope or cable, means for control-
ling the brake, and means for controlling
said device to increase the traction between 65
the sheave and rope or cable when the brake
is released, and decrease the traction when
the brake is applied.
9. In a traction elevator, the combination
with a car, of an electro-magnetic sheave, a 70
motor arranged to drive said sheave, and
means for varying the magnetism of said
sheave in proportion to the speed of the
motor.
10. In a traction elevator, the combination
of an electro-magnetic sheave, and means for
automatically varying a resistance in cir-
cuit with the windings of said sheave.
11. In a traction elevator, the combination
of an electric motor, an electro-magnetic 75
sheave connected to said motor, and means
for varying a resistance in circuit with the
windings of said sheave in proportion to
the counter-electro-motive-force of said
motor.

In testimony whereof, I have signed my
name to this specification in the presence of
two subscribing witnesses.

AUGUST SUNDH.
